HYDRAULIC TRACER VALVE FOR MACHINE TOOL

Victor Ruzick, Fullerton, and Harry C. Mix,
Anaheim, Calif.

Application November 4, 1957, Serial No. 48,326

Term of patent 14 years

(Cl. D78—1)

Figure 1 is a side view, in elevation, of a hydraulic tracer valve for machine tool embodying our new design;

Figure 2 is a top plan view thereof;

Figure 3 is a bottom plan view thereof; and

Figure 4 is a perspective view thereof.

The sides of the valve not shown are the same in appearance as the sides shown.

The dominant features of our new design reside in those portions shown in solid lines.

We claim:

The ornamental design for a hydraulic tracer valve for machine tool, as shown and described.
